The ornamental design for a spray for liquid media, as shown and described.

DESCRIPTION

FIG. 1: is a side perspective view of a spray for liquid media showing our new design;

FIG. 2: is another side perspective view of the spray shown in FIG. 1, whereas the actuation button is in the pressed position;

FIG. 3: is a side elevation view of the spray in FIG. 1 (the opposite side being a mirror image);

FIG. 4: is a top plan view of the spray in FIG. 1;

FIG. 5: is a front elevation view of the spray in FIG. 1;

FIG. 6: is a bottom plan view of the spray in FIG. 1;

FIG. 7: is a side perspective view of a second embodiment of a pump for liquid media as in FIG. 1, the difference being that some parts are shown in broken lines.

FIG. 8: is a another side perspective view of the spray in FIG. 7, whereas the actuation button is in the pressed position;

FIG. 9: is a side elevation view of the spray in FIG. 7 (the opposite side being a mirror image);

FIG. 10: is a top plan view of the spray in FIG. 7;

FIG. 11: is a front elevation view of the spray in FIG. 7;

FIG. 12: is a bottom plan view of the spray in FIG. 7; and, FIG. 13: is a back elevation view of the spray for liquid media.

The broken lines shown in these figures are for illustrative purposes only and form no part of the claimed design.
